UNITED STATES PATENT OFFICE.

LOUIS BRANDT, OF NEW YORK, N. Y.

DESIGN FOR BRAID.

SPECIFICATION forming part of Design No. 33,569, dated November 13, 1900:

Application filed October 16, 1900. Serial No. 33,300. Term of patent 3½ years.

To all whom it may concern:

Be it known that I, LOUIS BRANDT, a citizen of the United States, and a resident of the city of New York, borough of Manhattan, in the county and State of New York, have invented and produced a new and original Design for Braid, of which the following is a specification, reference being had to the accompanying drawing, forming a part thereof, in which is represented a plan view of a strip of braid embodying the features of my design.

The leading feature of the design consists in a central section, which is of loop formation, and in body-loops, which extend from the central section at each side, inclining in opposite directions from the side, but in direction of the same end of the central section. The body-loops are so arranged with reference to each other and with reference to the

central section that the said body-loops present in plan view a series of interlocking bow-ties.

A minor feature of the design consists in indentations in the body-loops, which add to the sheen of the material.

Having thus described my invention, I claim as new and desire to secure by Letters Patent—

The design for braid, herein shown and described.

In testimony whereof I have signed my name to this specification in the presence of two subscribing witnesses.

LOUIS BRANDT.
